UNITED STATES PATENT OFFICE.

HENRY C. MILLER, OF MILWAUKEE, WISCONSIN.

LOOSE-LEAF BINDER.

Application filed February 12, 1925. Serial No. 8,720.

To all whom it may concern:

Be it known that I, HENRY G. MILLER, a citizen of the United States, and resident of Milwaukee, in the county of Milwaukee and 5 State of Wisconsin, have invented new and useful Improvements in Loose-Leaf Binders, of which the following is a description, reference being had to the accompanying drawings, which are a part of this specification.

10 This invention relates to certain new and useful improvements in loose leaf binders and has as a general object the simplification of devices of this character.

Another object of this invention resides in 15 the provision of an improved loose leaf binder in which the shifting of one of the binder heads effects the connecting of the heads to clamp the loose leaves therebetween.

A further object of this invention resides 20 in the provision of a loose leaf binder in which added tension may be applied to the leaves between the binder heads, after the heads have been locked together, by rotation of the binder posts.

25 And a still further object of this invention resides in the provision of improved means for preventing the accidental loosening of the connection between the binder heads and the provision of means for facilitating the 30 application of added tension after the binders have been connected.

With the above and other objects in view which will appear as the description proceeds, my invention resides in the novel construction, combination and arrangement of parts substantially as hereinafter described and more particularly defined by the appended claims, it being understood that such changes in the precise embodiment of the 40 herein disclosed invention may be made as come within the scope of the claims.

In the accompanying drawings, I have illustrated two complete examples of the physical embodiment of my invention constructed 45 according to the best modes I have so far devised for the practical application of the principles thereof and in which:

Figure 1 is a fragmentary view of a loose leaf binder embodying this invention, parts 50 thereof being broken away and in section to more clearly illustrate details of construction;

Figure 2 is an enlarged view, partly in section and partly in elevation, taken on the 55 plane of the line 2—2 of Figure 1, the cover of the upper binder head being open and

one of the binder posts being in extended position;

Figure 3 is a fragmentary, detail view, partly in section and partly in elevation, 60 taken through one end of the upper binder head on the plane of the line 3—3 of Figure 2;

Figure 4 is a view similar to Figure 2 of a slightly modified form of my invention, and 65

Figure 5 is a fragmentary detail view of the means for locking the shiftable binder head against movement, said view being taken on the plane of the line 5—5 of Figure 4. 70

Referring now more particularly to the accompanying drawings, in which like numerals designate like parts throughout the several views, the numerals 5 and 6 designate upper and lower binder heads, respectively, 75 between which a body of leaves 7 is clamped by binder post members 8. The posts 8 are connected with the lower head 6 by a threaded stud 9 engaging an internally threaded member 10 riveted or otherwise secured there- 80 to, see Figures 1 and 4, and are movable into the upper head 5, in the manner herein- after described. Pivoted between lugs 11 at the ends of the binder heads, are the upper and lower covers 12 and 13, respectively, of 85 the binder.

Each post 8 in that form of my invention illustrated in Figures 1 to 3, inclusive, is formed in two sections 14 and 15 hingedly connected, as at 16, to permit the movement 90 of the section 15 from a position forming a continuation of the section 14 to a position at right angles thereto. The section 14 of each binder post is extensible, being formed of sections 17 and 18 connected by a relatively 95 long, reduced threaded shank 19 carried by one section and threaded in the bore of the next or adjacent section, there being as many sections as required to accommodate the body of leaves 7. 100

The section 14 is provided with one or more grooved or reduced portions 20 adjacent its pivot 16 for engagement in the reduced portion 21 of a key-hole slot formed in the adjacent end of the upper binder head, the large portion 22 of the key-hole slot being of a diameter sufficient to pass the largest diameter of the binder post. With this construction it will be apparent that the distance between the reduced por- 105 tions 20 and the lower binder head is set to approximately that of the thickness of 110

the body of leaves by the addition or removal of the necessary extension sections and before locking the binder.

With the large portions 22 of the key-hole slots in alignment with the posts, the upper binder head is pressed down to engage the leaves and then shifted sidewise, when the grooved portions 20 of the posts are in register with the key-hole slot, to engage the reduced portions of the post in the smaller portions of the key-hole slots. If it is desired to apply added tension to the leaves confined between the binder heads, the posts 15 may be rotated to further 15 thread the studs 19 into the adjacent extension sections, as will be apparent.

The upper binder head may be locked against accidental shifting to register the large portions of the key-hole slots with 20 the posts and consequently release the pressure thereon, by a member 23 pivotally mounted on the upper binder head adjacent one key-hole slot and provided with a curved portion 24 on its end adjacent the 25 key-hole slot for engagement behind the adjacent binder post after the reduced portion thereof has been engaged in the reduced portion of the key-hole slot. The end of the pivoted member opposite its curved portion 24 has an upstanding finger engaging member 25 formed thereon which serves to prevent accidental movement of the member 30 on its pivot when the hinged section 15 of the adjacent post is swung into the upper binder head. The section 15 when folded into the upper binder head provides a stop preventing the inward movement of the end 25 of the member 23 that is necessary to disengage the end 24 of the pivoted 40 member from the path of the adjacent post.

After the binder heads have been secured in the positions illustrated in Figure 1 and the sections 15 of the posts folded into the pocket or recess of the upper binder head, 45 the posts and the locking element are concealed by a hinged cover 26. The cover 26 is provided with one or more yieldable fingers 27 which bear on the sections 15 of the posts when the cover is secured closed by one or more readily releaseable latch 50 members 28 and effect the quick opening of the cover when the latches 28 are disengaged from their locking recess 29. Each latch member 28 is medially pivoted in the adjacent end of the upper binder head, as at 28', and pivotally connected therewith, as at 29', is a push button 30' which projects and is spring urged outwardly of the binder head end by a spring 31'.

60 The outer ends of the post sections 15 are preferably bifurcated, as at 30, and have pivoted therein a lift or finger engaging member 31 and a check or stop 32. The lifts 31 provide means for facilitating the 65 movement of the post sections from con-

cealed position to a position in line with the sections 14 and are movable laterally to provide a leverage for threading and drawing the post extension sections together to thus facilitate the placing of added pressure on the leaves 7. The stops 32 are normally in a lateral position and prevent the accidental removal of the upper binder head from the posts, it being first necessary to move the stops 32 on their pivots to positions in line with the sections 15 in order to prevent the withdrawal of the upper head from the binder posts.

In Figures 4 and 5, a slightly modified form of my invention is illustrated in which the posts 8 are formed of a plurality of threadedly connected extension sections without provisions for the folding of that portion of the posts extended above the upper head. In this form of my invention, that portion of the posts extending beyond the combined thickness of the binder heads and leaves project above the upper binder head and the reduced portions 20 of the posts may be formed in the sections or by 90 spacing adjacent extension sections, in the manner illustrated in Figure 4.

The extension sections are not tightly drawn together so that added tension is applied to the leaves when the extension sections are drawn together by rotation of the posts to take up any space between the sections. The stops 32, in this form of my invention provide the leverage for shortening the posts and also prevent the accidental 100 removal of the upper head from the posts.

The upper binder head is locked against shifting to accidentally release the binder by a member 33 pivotally secured, as at 34, to the binder head and having its free end 35 movable into the path of the adjacent binder post, in the manner illustrated in Figure 5. A raised projection on the upper binder head rides in an arcuate recess 37 formed in an outstruck portion 38 of the member 33 110 to limit the pivotal movement of the member 33.

From the foregoing description taken in connection with the accompanying drawings, it will be readily apparent to those skilled in the art to which an invention of this character appertains that I provide novel and improved means for effecting the locking of a loose leaf binder, and means which facilitate the speedy adjustment of 120 the binder.

What I claim as my invention is:

1. A loose leaf binder, comprising a pair of binder heads, a binder post carried by one head and having a groove therein, the binder post being engageable through a key-hole slot in the other binder head and shifting of said other binder head to engage the groove of the post in the small portion of the key-hole slot locking the binder heads 130

together, and means for applying a tension on the binder post after the binder heads are connected.

2. A loose leaf binder, comprising a pair of binder heads, a binder post including hinged sections, one of the sections thereof being connected with one binder head and passed through a key-hole slot in the other, said other section being foldable to lie within the other binder head, and the post section connected with the first-mentioned binder head having a reduced portion whereby said other binder head may be shifted to engage the reduced portion of said post section in the small portion of the key-hole slot to secure the binder heads together.

3. A loose leaf binder, comprising a pair of binder heads, a binder post including

hinged sections, one of the sections thereof being connected with one binder head and passed through a key-hole slot in the other, said other section being foldable to lie within the other binder head, and the post section connected with the first-mentioned binder head having a reduced portion whereby said other binder head may be shifted to engage the reduced portion of said post section in the small portion of the key-hole slot to secure the binder heads together, and means engageable behind the binder post when the reduced portion thereof is engaged in the small portion of the key-hole slot to secure said other binder head against shifting and consequently lock the binder heads together.

In testimony whereof I affix my signature.
HENRY C. MILLER.
